UNITED STATES PATENT OFFICE.

HENRY G. VOIGHT, OF NEW BRITAIN, CONNECTICUT.

CYLINDER-LOCK MECHANISM.

1,093,811.

Specification of Letters Patent.

Patented Apr. 21, 1914.

Original application filed March 18, 1913, Serial No. 755,101. Divided and this application filed July 3, 1913. Serial No. 777,236.

To all whom it may concern:

Be it known that I, HENRY G. VOIGHT, a citizen of the United States, residing at New Britain, Hartford county, State of Connecticut, have invented certain new and useful Improvements in Cylinder-Lock Mechanism, of which the following is a full, clear, and exact description.

This invention relates to cylinder lock mechanism and provides, in a device of this character, two actuating mechanisms operable by keys coöperating with the tumbler mechanism of the lock, one of these actuating devices being controllable by all of a series of keys used in connection with the lock, and the other of said actuating devices normally occupying what is designed to be an inoperative position but being movable and operable by a certain key or keys of the series. Such a construction may be utilized to secure a variety of results, one example of which is the actuation, through the normally inoperative device, of a special blocking and unblocking mechanism co-operating with a bolt-actuating mechanism controlled through the other actuating device of the lock.

A preferable embodiment of the invention is described in detail in the following specification taken in connection with the accompanying drawings forming part thereof.

In these drawings, Figure 1 is a view in side elevation, partly in section, of a cylinder lock embodying the present invention. Fig. 2 is a view in end elevation of the parts shown in Fig. 1. Fig. 3 is a view in side elevation of the cylinder lock with the second roll-back thereof operatively positioned by the long key. Fig. 4 is an end elevation of the lock shown in Fig. 3. Fig. 5 is a detail of the first or main roll-back. Fig. 6 is a detail of the second or auxiliary roll-back. Figs. 7 and 8 are, respectively, details of short and long keys respectively, designed to operate respectively the first and second roll-backs.

Referring to the drawings by numerals, 1 indicates the usual threaded barrel of a cylinder lock which in practice is screwed into the plate of the lock case to operate the boltage mechanism therein. The barrel is provided with the usual series of pin tumblers (not shown) and with the rotatable element or plug 2 journaled therein and co-

operating with the pin tumbler mechanism 55 in the usual manner. This rotatable plug is provided with the usual key hole slot 3 and at its inner end is shouldered down to provide an angular or squared portion 2^a which projects from the inner face of the barrel. 60 The key hole slot 3 extends through the plug and through this angular end extension.

A primary roll-back or cam arm 4 is provided, which cam arm has in its outer face a 65 slot 5 extending longitudinally thereof. This slot extends longitudinally of the cam arm from its outer end to substantially its center where it is decreased in depth, providing a shoulder 4^a which rests upon the upper face 70 of the angular end extension 2^a of the plug, the lower forward faces of the cam arm being rigidly secured to the end of said extension by any suitable means as the screws shown. The sides of the outer recessed face 75 of this cam adjacent its outer face, are channeled longitudinally, as at 6, to receive the second or auxiliary roll-back. This cam arm 4 is fixed relatively to the rotatable plug and will always rotate in the same arc. 80 The second or auxiliary roll-back or cam arm, which is carried by the first cam arm 4, moves relatively thereto, as will be seen, and normally occupies a fixed position from which it may be moved by the means herein- 85 after described to assume a second position relative to the first cam arm. This auxiliary roll-back comprises a sliding plate 7 positioned within the outer channeled face of the first roll-back and guiding within the chan- 90 nels 6 therein. The upper end of this plate 7 is provided with an outwardly offset end 8 forming the actuating portion of this aux- 95 illary roll-back, which offset projects out- wardly from and lies in a different plane from the actuating end of the first or pri- 100 mary roll-back. The channel 5 in the outer face of the first roll-back 4, above the shoul- der 6, provides a pocket 9 having a coiled spring 10, one end of which engages the cam arm 4 at the upper end of said pocket, and the other end of which spring is adapted to engage a pin 11 carried by and projecting from the inner or rear face of the sliding plate 7 and projecting through a slot 9^a in 10^a the front wall of said pocket. The coiled spring 10 acts against the pin 11 and nor- mally tends to move the sliding plate 7

downwardly in the channel 6 to position the lower end of said sliding plate below the upper edge of the key hole slot 3 in the rotatable plug so that said lower edge will be engaged by the forward end of a key and lifted against the tension of the coiled spring 10. The end face of the rotatable plug lies within the recessed face of the cam arm 4 and adjacent and rearwardly of the inner face of the sliding plate 7 of the auxiliary roll-back.

A series of keys are designed to be used in conjunction with such a cylinder lock as I have herein described, these keys being all bitted to coöperate with the pin tumbler mechanism so that the plug 2 may be rotated, and with it the primary cam arm or roll-back 4. The auxiliary roll-back, being carried by the primary roll-back, of necessity rotates with it. The two different positions which this auxiliary roll-back may assume may be operative and inoperative positions relative to a mechanism which it is designed to operate by means of this auxiliary roll-back. Certain keys of the series used will rotate the primary cam arm 4 with the auxiliary cam arm or roll-back carried thereby in one of these two positions. A certain key of the series is designed to coöperate with this auxiliary cam arm or roll-back to move it to the other position and at the same time is operative to rotate the plug and primary roll-back. This is accomplished by utilizing short keys, such as 12 (Fig. 7) for operating the primary cam arm or roll-back 4. These keys are not long enough to project in and engage their forward beveled ends with the sliding plate 7 so that when such keys are utilized only the mechanism controlled by the roll-back 4 will be operated. I provide, however, a certain key, such as 13, which I shall term a "long" key, which long key is bitted to coöperate with the tumbler mechanism so that the primary roll-back 4 can be rotated thereby, and which key is also of a length sufficient to engage its forward beveled end with the lower edge of the sliding plate 7 when said key is inserted, to thereby raise said plate and its cam end 8 relative to the primary cam arm and to a position where it may operate certain special mechanism so that a special key only, such as the long key 13, may control this special mechanism. When the long key is withdrawn, the coiled spring 9 will return the auxiliary cam arm or roll-back to its original position, which may be the inoperative position.

One specific form of mechanism in connection with which the present invention may be advantageously utilized is illustrated in my pending application, Serial No. 755,101, of which the present application is a division.

65 The structure herein described provides a

comparatively simple structure for effecting the ends desired. By utilizing in connection with such a single actuating mechanism an auxiliary cam arm, a double control is provided through a single actuating mechanism '70 and the necessity of providing, for the second control, a separate and auxiliary roll-back or its equivalent, is obviated.

It will be obvious that while I have herein described a particular structural embodiment of the invention, various changes in structure and in the relative arrangement of parts may be made within the spirit of the invention and the scope of the appended claims.

What I claim, therefore, and desire to secure by Letters Patent is:

1. As an article of manufacture, a cylinder lock embodying a key-controlled rotatable plug provided with a relatively fixed roll-back member, and a second roll-back member carried by and movable relative to the first.

2. As an article of manufacture, a cylinder lock embodying a rotatable plug, a roll-back member carried by and fixed relatively to said plug and rotating therewith, said plug and roll-back member being controlled and rotatable by a plurality of keys, a second roll-back member carried by the first and mounted for movement relatively thereto, and means whereby one certain of said plurality of keys may move said second roll-back member relatively to the first and may rotate both of said members simultaneously. 100

3. In a cylinder lock, a rotatable plug having a key-slot therein, a cam rigidly carried thereby, tumbler mechanism coöperating with said plug and operable by a plurality of keys to permit rotation of said plug 105 and cam, a second cam carried by said plug, movable relatively thereto and positioned in a different plane from said fixed cam, means normally positioning said movable cam in the line of said key-slot, one of said plurality of tumbler operating keys being arranged to engage said movable cam to move it relatively to said plug.

4. In a cylinder lock, a rotatable plug having a key-slot therein, a cam rigidly carried thereby, tumbler mechanism coöperating with said plug and operable by a plurality of keys to permit the rotation of said plug and cam, a second cam offset from and guided on said first cam and movable relative thereto and to said plug, spring means normally positioning said cam in the line of said key-slot, one of said tumbler operating keys being constructed to engage said aligned cam to move it relatively to said fixed cam 120 and plug.

5. As an article of manufacture, a cylinder lock provided with a key-actuated roll-back member and an auxiliary roll-back member carried thereby and movable rela- 13

tively thereto, said roll-back members being arranged to coact simultaneously with a certain key.

6. In a cylinder lock, a rotatable plug having a key-slot therein, a cam arm rigidly carried by said plug, tumbler mechanism cooperating with said plug and operable by a plurality of keys to permit rotation of said plug and cam arm, a second and auxiliary arm carried by and positioned in a different plane from said rigidly carried arm, means normally tending to hold said auxiliary cam

arm in one position, and means whereby a certain key of said plurality of keys may operate said tumbler mechanism and may move said auxiliary cam arm from such position and relatively to said rigidly carried cam arm, and may rotate said cam arms simultaneously.

HENRY G. VOIGHT.
